The ornamental design for a plush unicorn ride-on toy, as shown and described.

DESCRIPTION

FIG. 1 is a front perspective view of the design;

FIG. 2 is a rear perspective view of FIG. 1;

FIG. 3 is a front elevational view of FIG. 1;

FIG. 4 is a rear elevational view of FIG. 1;

FIG. 5 is a left-side elevational view of FIG. 1;

FIG. 6 is a right-side elevational front view of FIG. 1; and, FIG. 7 is a top plan view of FIG. 1.

The broken lines shown on the drawings depict portions of the plush unicorn ride-on toy that form no part of the claimed design.
